UNITED STATES PATENT OFFICE.

ENOCH M. VOGNILD, OF CHICAGO, ILLINOIS.

WINDOW-CLEANER.

1,317,840.

Specification of Letters Patent.

Patented Oct. 7, 1919.

Application filed June 30, 1916. Serial No. 106,791.

To all whom it may concern:

Be it known that I, ENOCH M. VOGNILD, a citizen of the United States, residing at Chicago, in the county of Cook and State of Illinois, have invented certain new and useful Improvements in Window-Cleaners, of which the following is a specification.

This invention relates to window cleaners, and its purpose is to provide an improved device of this kind which may be conveniently operated for effecting a thorough cleaning of windows, or other like objects.

The principal object of the invention is to provide a power-driven window cleaner having a movable washing element and a movable drying element. A further object is to provide a window cleaner having a movable washing element in combination with improved means for supplying water or other washing fluid thereto. Still another object is to provide a window cleaner having a heated drying element. A further feature relates to the provision of a rotatable washing element and a rotatable drying element, in combination with improved means for actuating these elements and controlling the operation thereof. Another object is to provide an improved construction and arrangement of parts in a power-driven window cleaner.

These and other objects of the invention will appear more clearly from the following specification, taken in connection with the accompanying drawings, in which embodiments of the invention are illustrated.

In the drawings—

Figure 1 is a front elevation of the preferred form of my improved window cleaner, showing vertical sections through certain parts of the apparatus.

Fig. 2 is a diagrammatic view, showing the circuits of the motor and heating coil.

Fig. 3 is an enlarged partial end elevation taken at right angles to the views shown in Fig. 1, showing the means for tilting the window cleaner proper with respect to the supporting member by which it is carried.

Fig. 4 is a sectional view, taken on the line 4—4 of Fig. 1, looking in the direction of the arrows.

Fig. 5 is a sectional view, taken on the line 5—5 of Fig. 1, looking in the direction of the arrows.

Fig. 6 is a sectional view, taken on the

irregular line 6—6 of Fig. 1, looking in the direction of the arrows.

Fig. 7 is a sectional view through the fluid tank, taken on the line 7—7 of Fig. 1.

Fig. 8 is a plan view of a split clamping ring for securing the covers on the washing and drying elements.

Fig. 9 is a front elevation of a modified form of my improved window cleaner, showing vertical sections through certain parts of the apparatus.

Fig. 10 is an elevation of the insulating plate of a heating member embodied in the form of construction illustrated in Fig. 9 showing the electrical heating coils assembled thereon.

Fig. 11 is an elevation of the rear side of the plate illustrated in Fig. 10, showing the contact rings to which the electrical heating element is connected; and

Fig. 12 is a side elevation, taken at right angles to the view shown in Fig. 9, showing certain parts in section.

Referring to Figs. 1 to 8, inclusive, of the drawings, it will be seen that the embodiment of my invention illustrated therein comprises a conical washing element 15 and a conical heating and drying element 16, both of which are arranged to rotate by means hereinafter to be described, and which are adapted to be used in succession on the window, or other object, being cleaned in order to effect a washing and drying thereof. The washing member 15 comprises a conical supporting member 17, which is preferably constructed of metal, such as brass or the like, this supporting member comprising a base 17^a which is attached to a supporting bracket 18, by which the washing member is carried. A hollow shaft 19 is attached to or formed integrally with the bracket 18, and extends downwardly therefrom in alignment with the vertical axis of the conical member 17. This shaft is hollow, for a purpose to be described, and is journaled in the spaced apart bearings 20. A groove pulley 21 is fixed on the shaft 19 between the bearings 20, and the rotation of this pulley by suitable driving means effects the rotation of the washing member 15 for cleaning purposes. Suitable collars or washers 22 are mounted on the shaft 19 beneath the lowermost bearing 20, and a suitable nut 23 threadedly engages the lower end of the shaft. The conical supporting

member 17 of the washing element is surrounded and covered by a cleansing or washing member 25, which may preferably be formed of woolen cloth, felt, or the like, and which is arranged to fit closely the member 17 and is adapted to be held in fixed position thereon by means of a split clamping ring 26 passing through a suitable hem which is provided around the lower edge of the member 25, this clamping ring being of lesser diameter than the base of the supporting member.

The member 17 is provided near its upper end with a transversely extending tube 28, which communicates with a downwardly extending tube 29. This tube forms a continuation of and may be in fact a part of the shaft 19, previously described, so that a communication is formed through said shaft to a pipe 30 which extends upwardly into the lower end of the shaft and forms a rotative engagement therewith. Suitable packing may be placed in the chamber 23^a of the nut 23, in order to effect a fluid-tight connection between the shaft 19 and the pipe 30, through which water or other washing fluid is supplied to the tube 29, and thence through the tube 28 to the outer surface of the supporting member 17, where the water or other fluid moistens the cleansing or washing member 25.

The pipe 30 leads upwardly from the lower end of the shaft 19 and communicates with a small chamber 32, which is formed in a supporting member 33. This chamber, in turn, communicates with a tank 34, which is carried by the member 33 and which is adapted to contain water or other washing fluid. The ends of this tank are preferably shaped to conform to the contours of the washing and drying elements, as shown, for instance, in Figs. 4, 5, and 6, and the side walls 34^a converge upwardly, being spaced inwardly from planes which are tangent to the washing and drying elements. The upper wall of the tank is provided with a detachable cap 34^b, through which the fluid may be passed into the tank.

The supporting member 33 and the bearings 20, previously described, are carried by suitable brackets 33^a and 20^a, respectively, which are secured to or formed integrally with the casing of an electric motor 35. The shaft 36 of the motor extends vertically from the casing 35 and carries at its upper end a small water wheel or vane 37, which is located in the chamber 32 and adapted to rotate therein when the motor is in operation. A suitable packing chamber 38 is formed in the member 33 around the shaft 36, this chamber being closed by a packing nut 39, whereby a fluid-tight connection is made between the shaft 36 and the member 33. It will be seen that the chamber 32 and the water wheel 37 form a centrifugal pump,

by means of which fluid in the tank 34 is driven through the pipe 30 to the tubes 29 and 28, through which the fluid passes to the outer surface of the member 17 of the washing element.

A double-grooved driving pulley 40 is fixed upon the shaft 36 between the nut 39 and the bearing 35^a of the motor casing, and a flexible belt 41 passes around this pulley and around the pulley 21, previously described, to effect the rotation of the washing element when the motor is in operation. A second flexible belt 42 passes around the other groove of the pulley 40, and thence around another pulley 43 which is fixed on a vertical shaft 44, journaled in the bearings 45 carried by suitable brackets 45^a, which are attached to or formed integrally with the motor casing. A collar 46 is fixed on the lower end of the shaft 44, and the upper end of the shaft is fixed to or formed integrally with a supporting bracket 47 which is attached to the base 48^a of a conical supporting member 48, which forms a part of the drying element 16. By means of this construction it will be apparent that the operation of the motor effects the rotation of the drying element at the same time that the washing element is operated. A drying member or cloth 49, formed preferably of flannel, or the like, seats upon and closely fits the conical supporting member 48, and is secured thereon by means of a clamping ring 50, which is similar to the clamping ring 26 previously referred to.

The member 48 is hollow, and has mounted therein a heating member 51, which comprises a porcelain or other insulating supporting post 52, having formed on the base thereof the inwardly projecting lugs 52^a, which are secured to the base 48^a of the conical member 48 and to the arms of the bracket 47 by means of screws 52^b or the like. A ring 53 is secured to the base 48^a by screws 53^a, and the ring is in turn secured to the conical walls of the member 48, thus permitting access to the interior of the drying member when desired. The porcelain supporting post 52 is preferably in the form of a truncated cone, and is provided on its peripheral surface with a spiral groove 54 which forms a seat for the electrical resistance element or wire 55, which is adapted to effect the heating of the drying element upon the passage of a suitable electric current therethrough. The ends of this resistance wire pass through suitable bushings 56 mounted in the base 48^a of the member 48 and the extremities of this resistance element are connected to the metallic contact rings 57 which are mounted on and insulated from the under side of the supporting bracket 48 concentrically with the axis of the shaft 44. An arm 59 extends outwardly from the upper bearing 45, and

has mounted thereon two contact members or brushes 60, each of which is arranged to bear upon one of the contact rings 57 and which are connected to the respective binding posts 61. The resistance wire 58 is preferably connected in series with a thermostatic circuit opener 62, which is located inside of the insulating member 52, as shown. This circuit opener comprises a thermostatic bar 62^a, which has its ends mounted on two insulating supports 63, and which has a binding post at one extremity adapted to be connected to one of the contact rings 57. This thermostatic bar may be composed of two plates of metal having different rates of expansion, so that when the bar becomes heated it will bend and thus break contact at a predetermined temperature with the adjustable contact screw 62^b, which is connected to one end of the electrical heating element and which may be varied in its position with respect to the insulating support 64. By means of this device the circuit of the heating coil is automatically opened when the drying element has reached a predetermined temperature, thus preventing injury to the drying cloth 49, and making it possible to secure any desired degree of temperature. When the drying element cools after the circuit has been opened the circuit opener may again close the circuit, and thus operate intermittently to maintain an even temperature.

The motor 35 is carried by a bracket 65, which is mounted between two plates 66^a of a socket member 66 carried by or formed integrally with a pole 68. A pin 67, passing through the members 65 and 66^a, forms a pivotal connection between those members, thus permitting tilting of the motor and the washing and drying elements carried thereby with respect to the socket member 66, which is mounted upon the supporting pole, or the like, 68. The motor and parts carried thereby may be secured at the desired inclination with respect to the supporting pole by means of a dog 69, which is slidably mounted in the socket member 66 and arranged to engage any suitable one of the notches 65^a which are formed in the lower arcuate surface of the bracket 65. A coiled spring 70, mounted in the socket member 66, serves normally to move the dog upwardly into engagement with one of the notches, but the dog may be withdrawn from such engaging position by means of a stem 71 which is attached to the dog, and which extends downwardly through the socket member and to a convenient point on the pole, where it is pivotally connected to an operating latch 72. This latch is pivoted at 72^a on the pole 68, and it may be conveniently manipulated by the operator to release the dog 69 when it is desired to change the inclination of the washing and

drying members with respect to the axis of the supporting pole 68. The socket member 66 carries an angularly disposed plate or bracket 73, which is apertured to be engaged by a link 74 carrying the finger hold 75 at the lower end thereof. This link is pivotally connected at its upper end to the operating arm 76^a of a valve 76, which is placed in the pipe 30, as previously described. By means of this construction the operator may regulate the flow of cleaning fluid through the pipe 30 to the washing element.

A flexible electric conduit 77 leading from a suitable source of electrical energy extends upwardly adjacent the pole 68 and socket member 66, being secured thereto, if desired, and this conduit carries suitable electric conductors, by means of which a circuit is formed between the source of supply and the electric motor which is connected to the circuit by means of the binding posts 79. A branch conduit 78 leads from the conduit 77 and carries suitable conductors, by means of which an electrical connection is made with the binding posts 61, which serve as terminals for the circuit of the electrical resistance element which is mounted within the drying element 16. These circuit connections are illustrated diagrammatically in Fig. 2. The circuits of the motor and drying element may be independently regulated by means of switches 77^a and 78^a which are mounted in a casing on the pole.

In the operation of this device the dog 69 is first operated to effect the desired inclination of the washing and drying elements with respect to the supporting pole 68, and the device is then moved to a position with the conical washing element 15 bearing on the surface of the window to be cleaned. The motor 35 may be started to cause the rotation of the washing and drying elements either before or after moving the device to an operative position with respect to the window. The operator then moves the washing element over the window surface after having opened the valve 77 to permit the washing fluid to be forced by the centrifugal pump at the base of the tank through the pipe 30 and tubes 29 and 28 to the outer surface of the conical member 17. During the operation of moving the washing element over the window, the valve may be regulated to vary the amount of the washing fluid which is admitted to the washing member 25 carried by the member 17. During the operation of washing the window by means of the washing element 15 the drying element 16 may be caused to engage the window and to follow the movements of the washing member, so that the complete operation of washing and drying the window is affected by one operation of the device over the surface of the window. It will be seen

that the construction and arrangement of the tank 34 permits the simultaneous operation of both of the elements 15 and 16, since the lateral walls 34^a of the tank are inclined and located inwardly from planes which are tangential to the conical washing and drying elements. However, instead of using the washing and drying elements simultaneously, either element may be employed alone by supporting the pole 68 in such a position as to cause one element only to engage the surface of the window. In this way the window may be washed in one operation, and then dried by a succeeding movement of the drying element over the surface thereof. It will be seen that the heating member of the drying element may be controlled by the switch 78^a independently of the operation of the motor, so that it is unnecessary to maintain the drying element in a highly heated condition when it is not in operation, or the drying element may be used without being heated if desired. The heating member of the drying element operates to heat the interior of the member 48, so that a highly heated chamber is provided within the drying element, and this heat is transmitted through the walls of the member 48 to the drying cloth 49, thereby serving to prevent an undue accumulation of moisture in the cloth and also to effect evaporation of the moisture on the surface of the window. By means of this device the window is more thoroughly and quickly dried than is possible by the use of ordinary means, and streaks or other undesirable effects on the surface of the window are prevented. Although the heating member serves to maintain the drying member 49 in a substantially dry condition, it will be apparent that at any time during the cleaning operation the cloths or other members 25 and 49 may be removed if they become soiled or unduly saturated with moisture, and new washing or drying cloths, or the like, can be placed on the conical members 17 and 48 after releasing the split clamping rings 26 and 50. The particular advantage of the form of cleaning device described above is that the conical washing and drying elements may be manipulated to contact with the corners and other inaccessible parts of the window surface in order to effect cleaning of the entire surface of the window. During the cleaning operation the latch 72 may be operated to change the inclination of the washing and drying elements with respect to the supporting pole in order to insure a perfect contact of those elements with the surface being cleaned, and the link 74 and switches 77^a and 78^a may be operated to control the valve 76, the circuit of the motor, and the circuit of the electrical heating element. All of these controlling devices may be operated from a con-

venient position on the pole 68, so that the device may be conveniently controlled by one person when in operation.

Referring to Figs. 9 to 12, inclusive, of the drawings, it will be seen that the modified form of my invention comprises a washing element 80 and a drying element 81, which are different in form from the corresponding elements embodied in the previously described form of my invention. The washing element 80 comprises a metallic supporting member 82, which is hollow and circular in form, being provided with an outer wall 82^a, an inner wall 82^b, and an annular inclined wall 82^c. The wall 82^c is preferably formed integrally with the wall 82^a. Projecting inwardly from the inner surface of the wall 82^c are lugs 82^d, and the outer wall 82^a is then attached to the lugs by means of screws, or other suitable means. The washing member 83, preferably a cloth of suitable material, is seated on the outer plane surface 82^a, and its edges extend around the annular inclined wall 82^c, being secured in position by a detachable split clamping ring 84. The inner wall 82^b of the supporting member is fixed to the hub and the rim of a relatively large gear 85. This gear is fixed upon the reduced part 85^a of a supplementary hub 85^b, which is journaled upon the stub shaft 86 projecting from the upper enlarged part 87 of the bracket 88 carried by or formed integrally with the casing of an electric motor 89. The horizontally extending shaft of the motor has secured thereon a driving pinion 90, which meshes with the gear 85, thereby causing the rotation of the washing element when the motor is in operation. A lock nut 91 engages the threaded extremity of the reduced part 85^a of the supplementary hub, and serves to maintain the inner wall 82^b and the gear 85 securely fixed upon the supplementary hub 85^b. Another nut 92 engages the threaded extremity of the stub shaft 86, and maintains the hub and gear on said shaft. It will be apparent that the outer wall of the washing member may be assembled in position on the supporting lugs 82^d after the nuts 91 and 92 have been assembled in position.

The tank 93 for washing fluid is mounted upon the enlarged part 87 of the bracket 88, and the upper wall of this tank is provided with a detachable cap 93^a, which may be removed to permit the filling of the tank with washing fluid. A duct 94 leads through the base of the tank, and through the member 87 and stub shaft 86 to the end of the latter, where the fluid may pass through the centrally located aperture 95^a to the outer surface of the wall 82^a, or it may be carried outwardly within the washing element by the centrifugal force of the latter, whence it will pass through the aper-

tures 83, which are located at intervals adjacent the outer periphery of the wall 82, and which lead from the interior chamber of the supporting member to the outer surface thereof. The flow of fluid through the duct 94 may be controlled by the valve 96, which is operated by a lever arm 97. A coil spring 98 serves normally to maintain the valve in closed position, and the valve 10 may be opened by means of a link 99, which is pivotally connected to the lever 97 and which extends downwardly, terminating in a finger hold 100.

The drying element 81 of this form of the invention comprises a circular hollow supporting member 103, which is constructed in the same manner, and is in all respects similar to the member 82 of the washing element, except that no apertures are provided through the outer wall thereof. A drying member 104, formed of cloth, chamois skin, or the like, seats upon the outer wall 103 of the supporting member, and is secured in position by means of a split clamping ring 105, which maintains the edges of the drying cloth in engagement with the annular inclined wall 103. The inner wall 103 is secured to the hub 106 and to the rim of the gear 106, which is driven by a pinion 107 fixed on the end of the shaft of the motor 89 opposite the pinion 90. The gear 106 is fixed upon the reduced part 106^a of the supplementary hub 106^a, which is journaled upon the stub shaft 108 carried by the enlarged part 87 of the bracket 88. A lock nut 109 clamps the member 103 and the gear in fixed position on the supplementary hub.

A circular plate 110, formed of porcelain, or other insulating material, is mounted on the end of the stub shaft 108, and seats against the nut 109, where it is held in fixed position by the lock nut 111, which engages the reduced threaded extremity of the stub shaft. The plate 110 is provided on its outer face with a spiral projection 112, which is inclined away from the axis of the shaft to form a spiral groove in which the electrical resistance or heating element 113 is seated. The ends of this resistance element pass through suitable bushings 114, which lead through the inner wall 103 and through the web of the gear 106. The extremities of the resistance element are connected to contact rings 115, which are fixed on the gear 106 concentrically with the axis thereof, so that as the gear rotates these contact rings will make contact with suitable brushes 116, which are carried by the bracket 88 and connected by the conductors 117 to a suitable source of electric energy. It will be understood that after the plate 110 and the member 103 have been assembled on the supplementary hub 106^a, the outer detachable wall 103 may be placed

in position and fastened to its supporting ring by screws, or the like. The cracks or joints may then be brazed, or otherwise treated, if desired, in order to prevent excess of moisture to the heating chamber within 70 the member 103.

The motor 89 is carried by a bracket 120, which is pivotally connected by a pin 121 to a socket member 122. A dog 123, slidably mounted in the socket member, is adapted to 75 engage any suitable one of the notches 120^a formed in the lower arcuate surface of the bracket, whereby the inclination of the motor and the washing and cleaning elements may be varied with respect to the supporting pole 125, to which the socket member 122 is attached, or with which it is formed. A coiled spring 126 serves normally to maintain the dog in engagement with one of the notches, but the dog may be withdrawn by 80 means of an operating stem or rod 127, which extends downwardly through the socket member and is pivotally connected to an operating latch 128. This latch is in turn pivoted at 129 on the socket member. 90 The link 99, previously described, passes through a suitable bracket 130 carried by the socket member 122.

A suitable flexible conduit 119 is mounted adjacent the pole 125, and contains suitable 95 electric conductors leading from a source of supply to the binding posts 118 of the motor. Suitable switches 132 and 133 are connected in the circuits of the motor and the heating member, and are mounted on the 100 pole 125, so that the circuits can be conveniently controlled by the operator.

The operation of the last described form of this invention is in general similar to that of the preferred form previously described, 105 but in this form the surfaces which are in contact with the window pane are plane surfaces and the washing and cleaning elements rotate about axes which are normal to the surface of the window pane. It will be seen that in this form a larger washing surface is in contact with the window, and this washing surface has a rotary movement on the window surface which is very desirable for effecting a thorough cleaning. The flow 110 of cleaning fluid may be regulated by the valve 96, and the inclination of the cleaning and drying elements with respect to the handle may be varied, as will be apparent from the foregoing description, and in the 115 operation of this device the washing and drying elements are used successively on the surface of the window, instead of simultaneously, so that it may be convenient to render the heating element inoperative by 120 means of the switch 133, when the washing element is in operation.

Although I have shown and described two 125 embodiments of this invention, it will be understood that it may be constructed in vari- 130

ous forms without departing from the scope of the invention as defined in the appended claims.

I claim:

5. 1. In a device of the class described, a pole, a movable washing element, a movable wiping and heating element, means for supporting both of said elements adjacent one end of said pole with parts of their operating surfaces lying in one plane, and means for operating said elements in unison.
10. 2. In a device of the class described, a supporting pole, a motor mounted on the end of said pole, a supporting frame carried by said motor, a conical washing element rotatively mounted on said frame, a conical drying element mounted on said frame, said washing element and said drying element having parts of their surfaces lying in one plane whereby they engage a surface simultaneously, and operating connections from said elements to said motor for rotating said elements simultaneously about their axes.
15. 3. In a device of the class described, a supporting pole, a motor mounted on the end of said pole, a supporting frame carried by said motor, a conical washing element rotatively mounted on said frame, a conical drying element mounted on said frame, said washing element and said drying element having parts of their surfaces lying in one plane whereby they engage a surface simultaneously, operating connections from said elements to said motor for rotating said elements simultaneously about their axes.
20. 4. In a device of the class described, a supporting pole, a motor mounted on the end of said pole, a supporting frame carried by said motor, a conical washing element rotatively mounted on said frame, a conical drying element mounted on said frame, said washing element and said drying element having parts of their surfaces lying in one plane whereby they engage a surface simultaneously, operating connections from said elements to said motor for rotating said elements simultaneously about their axes, a tank for washing fluid mounted on said frame between said washing element and said drying element, and means for supplying fluid from said tank through the interior of said washing element to the outer surface thereof.
25. 5. In a device of the class described, a supporting pole, a motor mounted on the upper end of said pole, a frame carried by said motor, a conical washing element having a shaft journaled in said frame, driving connections from said motor to said washing element, a fluid supply tank mounted on said frame, means for supplying fluid from said tank to the surface of said washing element, said last-named means leading through the interior of said washing element, means for controlling said fluid supply, and means for tilting said frame with respect to the axis of said pole.
30. 6. In a device of the class described, a hollow rotatable washing element, a covering therefor, means for rotating said washing element, means for supplying a fluid to said covering by discharging said fluid at a point between the hollow element and said covering, a pole for supporting said element and both of said means, and means for varying the inclination of said washing element with respect to said pole.
35. 7. In a device of the class described, a washing element, a shaft upon which said element is mounted, driving means operatively connected to said shaft to rotate the same, a duct leading through said shaft and said washing element to the outer surface of the latter, means operatively connected to said duct to supply a washing fluid therethrough during the operation of said driving means, means operated by said driving means for controlling said fluid supply means, and independent means for manually controlling said fluid supply.
40. 8. In a device of the class described, a washing element comprising a rigid supporting member and a cover therefor, a shaft on which said element is mounted, a bearing for said shaft, a tube extending through said shaft and supporting member to the outer surface of the latter, a receptacle for containing fluid, a pipe leading from said receptacle and operatively connected to said tube, means for rotating said washing element, and means actuated by said last-named means for forcing the fluid from said receptacle to the washing element.
45. 9. In a device of the class described, a pole, a motor carried thereby, a bracket extending outwardly from said motor, a supporting member journaled in said bracket and operatively connected to said motor, a hollow element positioned on said supporting member, a covering for said hollow element, means for saturating said covering with a cleansing fluid by discharging the same into contact therewith at a point between said covering and the outer face of said hollow element, and means at the control of the operator for regulating the flow of said fluid.
50. 10. In a window washing machine, a pole, a motor pivotally mounted on one end thereof, a tank and a washing element supported adjacent said motor by supporting means extending therefrom, means connecting said tank and said washing element for conducting a cleansing fluid from the former to the latter, the drive shaft of said motor terminating in said tank, and means carried thereby for producing a positive feed of said fluid through said conducting means to said washing element.
55. 11. In a device of the class described, a pole, a motor carried thereby, a bracket extending outwardly from said motor, a hollow shaft journaled in said bracket and operatively connected to said motor, a supporting base mounted on one end of said shaft, a hollow element positioned on said supporting base, a covering for said hollow element, a tube operatively connected to said hollow shaft and extending through said hollow element and terminating on the face thereof adjacent the underside of said

covering, and means for supplying a cleansing fluid to said covering by causing said fluid to flow through said hollow shaft and said tube.

- 5 11. A device of the class described comprising an operating pole, a motor adjustably mounted on one end thereof, supporting members rigidly secured to the casing of said motor and extending outwardly 10 therefrom, a washing element rotatably supported on one of said members, a dry-

ing element rotatably supported on another of said members, means operatively connecting said elements to the drive shaft of said motor, and a tank supported on the 15 other of said members and adapted to contain cleansing fluid to be supplied to said washing element.

In testimony whereof I have subscribed my name.

ENOCH M. VOGNILD.

Copies of this patent may be obtained for five cents each, by addressing the "Commissioner of Patents, Washington, D. C."
